UNITED STATES PATENT OFFICE.

PHILLIP EBELING, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A PIECE OF GLASS.

47,284.

Specification for Design.

Patented May 4, 1915.

Application filed June 27, 1914. Serial No. 847,758. Term of patent 7 years.

To all whom it may concern:

Be it known that I, PHILLIP EBELING, a citizen of the United States, and residing at Moundsville, in the county of Marshall and State of West Virginia, have invented a certain new, original, and ornamental Design for a Piece of Glass, of which the following is a specification, reference being had to the accompanying drawings, forming a part thereof, wherein—

Figure 1 is an elevation of a piece of glass embodying the new design, and Fig. 2 is a section taken on line 2—2 of Fig. 1.

The design is embodied in a piece of glass having a surface thereof formed with cube-

like configuration as shown. Since the glass is clear or translucent the flat faces and angles of the configuration produce a multiplicity of reflecting surfaces which are observable when looking through the smooth or unconfigured surface of the piece as well as when looking at the configuration directly or not through the glass.

I claim:—

The ornamental design for a piece of glass, substantially as shown and described.

PHILLIP EBELING.
